(57) **CLAIM**

The ornamental design for a shooting target mounting assembly, as shown and described.

DESCRIPTION

FIG. 1 is a perspective view of a shooting target mounting assembly in accordance with my design;

FIG. 2 is an exploded perspective view of the shooting target mounting assembly of FIG. 1, showing the upper member and lower member thereof separated for clarity of illustration;

FIG. 3 is a top plan view of the shooting target mounting assembly of FIG. 1;

FIG. 4 is a first end elevation view of the shooting target mounting assembly of FIG. 1; a second end elevation view being a mirror image thereof;

FIG. 5 is a first side elevation view of the shooting target mounting assembly of FIG. 1;

FIG. 6 is a bottom plan view of the shooting target mounting assembly of FIG. 1;

FIG. 7 is a second side elevation view of the shooting target mounting assembly of FIG. 1;

FIG. 8 is a top plan view of the upper member of the shooting target mounting assembly of FIG. 2 shown separately for clarity of illustration;

FIG. 9 is a first end elevation view of the upper member of the shooting target mounting assembly of FIG. 2 shown separately for clarity of illustration; the second end elevation view being a mirror image thereof;

FIG. 10 is a first side elevation view of the upper member of the shooting target mounting assembly of FIG. 2 shown separately for clarity of illustration;

FIG. 11 is a bottom plan view of the upper member of the shooting target mounting assembly of FIG. 2 shown separately for clarity of illustration;

FIG. 12 is a second side elevation view of the upper member of the shooting target mounting assembly of FIG. 2 shown separately for clarity of illustration;

(Continued)

FIG. 13 is a top plan view of the lower member of the shooting target mounting assembly of FIG. 2 shown separately for clarity of illustration;

FIG. 14 is a first end elevation view of the lower member of the shooting target mounting assembly of FIG. 2 shown separately for clarity of illustration; the second end elevation view being a mirror image thereof;

FIG. 15 is a first side elevation view of the lower member of the shooting target mounting assembly of FIG. 2 shown separately for clarity of illustration;

FIG. 16 is a bottom plan view of the lower member of the shooting target mounting assembly of FIG. 2 shown separately for clarity of illustration; and,

FIG. 17 is a second side elevation view of the lower member of the shooting target mounting assembly of FIG. 2 shown separately for clarity of illustration.
